ENVELOPE

James C. Stocks, Atlanta, Ga.

Application June 13, 1935, Serial No. 26,469

1 Claim. (Cl. 229—85)

This invention relates to envelopes and particularly to means permitting the quick and ready opening of the envelope. Envelopes containing letters or first-class matter are carefully sealed and oftentimes when the enclosure fills up the envelope, it is difficult to tear the envelope across or open it so that the enclosure may be removed. It is oftentimes necessary to hold the envelope up to a strong light in order 5 to determine the location of the contents before the recipient dares to tear the envelope open, as unless this is done, the tearing off of one end of the envelope is likely to tear off the end of a letter or check, or the like. This also 10 oftentimes results in the defacement of the face of the envelope and possibly the tearing away of a portion of the return address.

The object of the present invention is to provide an envelope which in most respects is constructed after the manner of any ordinary envelope but in which one of the end flaps is provided with a transversely extending slit, which is in such position that it will not be liable to be accidentally torn, but which permits the insertion of a finger to tear this end flap across and permit the end flap to be opened up and thus remove the contents of the envelope without in any way affecting or defacing the front of the envelope, and without in any way tending 25 to injure the contents of the envelope.

My invention is illustrated in the accompanying drawing wherein:

Figure 1 is a fragmentary elevation of the back of an envelope after the envelope has been sealed and as it would pass through the mails;

Figure 2 is a fragmentary section of the envelope with the envelope angularly bent so as to open the slit and permit the insertion of a finger;

Figure 3 is a like view to Figure 1 but showing the manner in which the finger is used after insertion in the slit to tear the envelope open;

Figure 4 shows the end flap of the envelope torn away and pulled open to thus permit the removal of the contents.

Referring to these figures, 10 designates an ordinary envelope such as is commonly used today, having the top flap 11, the bottom flap 12 and the end flap 13. The end flap 13 is

gummed to the margin of the bottom flap 12 at 14 and, of course, when the envelope is closed, the top flap 11 is brought down over the bottom and end flaps and gummed thereto in the usual manner. My invention consists in placing in an 5 end flap 13 the slit 15, which extends parallel to the end edge of the envelope and may have any desired or convenient length. This slit 15 is disposed inward from the extreme end of the envelope in a position where it will be somewhat 10 protected and not likely to be torn or come in contact with the fingers of the postman or those who cancel the stamps.

In opening an envelope of this kind, the envelope is bent at one end angularly, as shown 15 more or less diagrammatically in Figure 2, so that the slit 15 will open slightly, thus permitting a finger to be inserted within the slit, and then the finger is shifted laterally beneath the flap 12 and beneath the flap 11, as shown by the dotted lines in Figure 2, so as to tear the flap 13 on the line of the slit 15, as at 15a, in opposite directions, thus entirely freeing the flap 13 and permitting this flap to be pulled open, as shown in Figure 4. Then the contents may be readily 20 25 removed intact.

While I have illustrated this slit 15 as applied to a particular form of envelope such as the standard correspondence envelope commonly manufactured, it is to be understood that my 30 invention may be applied to other forms of envelopes without departing from the spirit thereof.

What is claimed is:

An envelope comprising a body sheet having a 35 bottom flap, a top flap and end flaps, the end flaps being gummed to the bottom flap and the top flap extending over the end flaps and adapted to be gummed thereto, one of said end flaps being provided with a straight slit extending 40 parallel to one end of the envelope and terminating short of the adjacent edges of the top and bottom flaps whereby to permit the insertion of a finger in the slit and to permit the tearing of the envelope along the line of said slit to 45 thereby detach the outer portion of the slotted end flap from the top and bottom flaps and permit the opening of the end flap.
